UNITED STATES PATENT OFFICE.

LEON WYGODSKY, OF NEW YORK, N. Y.

LIQUID-FUEL BURNER.

1,185,272.

Specification of Letters Patent. Patented May 30, 1916.

Application filed October 4, 1915. Serial No. 53,881.

To all whom it may concern:

Be it known that I, LEON WYGODSKY, a subject of the Czar of Russia, and a resident of New York, in the county of New York 5 and State of New York, have invented certain new and useful Improvements in Liquid-Fuel Burners, of which the following is a specification.

My invention relates generally to liquid 10 fuel burners, and particularly to that type thereof known as "torches"; particularly torches designed to burn kerosene and heavy oils.

Torches of the type to which my invention 15 relates comprise means for atomizing liquid fuel by the aid of air or other gas under pressure, the resulting jet of atomized fuel burning readily. Most of the torches of the type referred to use gasoline 20 as the fuel, and work unsatisfactorily, if at all, with kerosene and heavier oils. For the proper combustion of kerosene, and, particularly, for the proper combustion of oils heavier than kerosene, extremely fine atomi- 25 zation is required; and such extremely fine atomization is effected by the atomizing device of the torch herein described.

My invention comprises a novel construction of liquid fuel burner, and particularly, 30 a novel construction of the nozzle thereof, including the atomizing device.

The object of my invention is to improve and simplify liquid fuel torches of the type referred to, and to render the same capable 35 of burning satisfactorily, kerosene and heavier oils.

I will now proceed to describe my invention with reference to the accompanying drawings, and will then point out the novel 40 features in claims.

In said drawings: Figure 1 shows a central vertical section of a complete torch embodying my invention. Fig. 2 shows, on a larger scale, an axial section of the discharge end of the nozzle thereof, and of the fuel atomizing device forming a part of that nozzle. Fig. 3 shows a transverse section of the spraying device on the line $x-x$ of Fig. 2.

50 In the drawings, 1 designates a fuel reservoir having an inlet opening 2 and an outlet opening 3, in which latter opening is fitted one end of a bent nozzle 4, the other end of said nozzle being provided with an atomizing device 5 of a construction herein-after described. The nozzle 4 has an inte-

rior duct 6 for the supply of liquid fuel from the reservoir to the atomizing device, and has also another duct 7 for the supply of compressed air or other gas under pressure to the atomizing device; such air or other gas being conveyed to the duct 7 by means of a pipe 8. Within the reservoir 1, the nozzle 4 is provided with a depending tube 9 extending nearly to the bottom of the reservoir 1, the bore of this tube forming a substantial continuation of the duct 6; such tube 9 being, of course, open at the bottom.

The atomizing device comprises two members 10 and 11, each tapering or cone-shaped 65 at its outer end, the member 11 surrounding the member 10, and having a discharge orifice 12, there being a contracting space 13 between the conical end portion of member 10 and the inside wall of the conical end 75 portion of member 11. Member 10 has an interior bore 14 forming a continuation of the bore 6 of the nozzle, and contracting near its end to a small discharge orifice 15.

Member 10 is, in general form, an externally 80 screw threaded plug fitting into a screw threaded recess 16 of the nozzle 4 and having a base portion 17 of somewhat smaller diameter which has a force fit in a corresponding recess 18 of nozzle 4. Member 11 is a sleeve screw-connected to member 10, the rear portion of this sleeve having a force fit in a recess 19 provided in the end of nozzle 4. From the rear of member 11 forwardly, a recess 20 is provided between members 10 and 11, and the compressed air duct 7 communicates with the recess 19 and so with this space 20. Member 10 has flattened portions 21 on two sides, the result being the provision of flow spaces 22 extending from the air circulation space 20 forward to the tapering space 13 between the conical portions of members 10 and 11.

It will be seen that, by reason of the construction described, air under pressure passing from duct 7 into circulation space 20, has free opportunity for circulation around the plug 10 and so passes through both flow spaces 22 into the tapering space 13 and thence out through the discharge orifice 12. 100 Air under pressure issuing in that manner around a centrally orificed member such as member 10, exerts a powerful inductive action, tending to draw fluid out through the central passage and discharge perforation of 105 that member; and also exerts a powerful atomizing action on liquid so drawn out of

- the central orifice of the member 10 and discharged through the orifice 12 of member 11. I have found that the atomizing device constructed as described atomizes kerosene and heavier oils of the grades known as fuel oil, so finely that very perfect combustion is produced; an air pressure of about thirty pounds or greater being commonly employed.
- 10 The atomizer may be adjusted by screwing the cone 11 backward or forward upon the cone 10. Because of the force fit of the portion 17 of plug 10 in the recess 18 of the nozzle, and the tightness of the screw threads of such plug in the recess 16, and because of the force fit of the rear portion of the plug 11 in the recess 19 of the nozzle, no trouble is experienced from leakage of air or oil. An important feature in this 15 connection is the thinning down, as indicated, of the rear portion of the plug 11, incident to the formation of the circulating space 20; for this thinning down of the rear portion of the plug 11 decreases the 20 stiffness of the rear portion of the plug to such an extent that the air pressure in the space 20 expands that plug slightly insuring a tight fit between the plug and the recess 19 of the nozzle.
- 25 Preferably the flame from the atomizer is projected through a member 23 lined with refractory heat-insulating material 24, such as asbestos. Without this member 23 I have noted, in some cases, a tendency 30 for the flame to be blown out if the air pressure rises too high; but when this member 23, lined with refractory material, is employed, no such tendency is noted, but to the contrary, the flame is rendered more 35 intense.
- An important advantage of the torch above described is, that all the adjustment which may be required from time to time, is effected at one point only and by the turning 40 of one member only. Certain former torches intended for the use of kerosene and heavier fuel, of which I am aware, have comprised a number of adjustment devices; adjustment of one of such adjustment 45 devices, effecting, more or less, the conditions to be controlled by the other adjustment device or devices, the result being that the proper adjustment of such torches by ordinary men is rendered practically impossible; but since, in my torch, there is but one member to adjust, any ordinary workman 50 can adjust the torch with reasonable accuracy. It will be appreciated that for proper operation of a torch of this type, and for 55 the fine atomization of heavy fuel oils, absolute concentricity of the two members 10 and 11 is absolutely necessary. This absolute concentricity is assured by the way in which the two members 10 and 11 are connected to the nozzle 4. The recesses in this
- nozzle, into which the members 10 and 11 fit are rarely made exactly concentric; and it is the fit of these members 10 and 11 in these recesses, rather than the fit of the screw threads by which the member 10 is secured to the nozzle, and by which the member 11 is mounted upon the member 10, that the exact concentricity desired is obtained. The construction described also obviates the use of lock nuts or $\frac{1}{4}$ in nuts to hold the members tightly. This torch requires no preheating of the oil, or the nozzle, or atomizing device, in order to enable it to operate successfully with even heavy fuel oils; by which I mean oils which are sufficiently fluid at ordinary temperatures to permit them to flow under the inductive action induced by the air jet. An advantage of the torch is that the oil is not under pressure in the reservoir and therefore no danger attends its use. The refractory lining of the hollow member or chimney 23 through which the flame is projected, besides acting to avoid chilling of the outer portions of the combustible spray-stream, also has a catalytic or wall-action greatly facilitating combustion.
- What I claim is:—
1. A liquid fuel burner comprising a nozzle having a fuel-supply duct within it, a plug screw-threaded within said nozzle and having an unthreaded portion fitting closely within a corresponding recess of said nozzle and serving to center said plug with respect to said nozzle and also to form an anti-leakage joint therewith, said plug having a duct forming a continuation of the duct of the nozzle and contracting to a small discharge orifice, the discharge end of such plug tapering, and a sleeve surrounding said plug and screw-threaded thereto, and having an unthreaded portion fitting closely at one end into a corresponding recess of said nozzle and thereby centering the sleeve with respect to said nozzle and also forming an anti-leakage joint therewith, the other end of said sleeve having a discharge opening registering with the discharge opening of said plug, said sleeve formed internally to provide a contracting space between said sleeve and the discharge end of said plug, the structure comprising a flow space for the passage of air under pressure through such contracting space and the discharge outlet of said sleeve.
2. A liquid fuel burner comprising a nozzle having a fuel supply duct within it, a plug fitting closely into a corresponding recess of said nozzle and having a duct forming a continuation of the duct of that nozzle, and contracting to a small discharge orifice, the discharge end of said plug tapering, and a sleeve surrounding and mounted upon said plug and fitting closely at one end into a corresponding recess of said nozzle.

zle, the other end of said sleeve having a discharge opening registering with the discharge opening of said plug, said sleeve formed internally to provide a contracting space between said sleeve and the discharge end of said plug, said plug being cut away at one or more points to provide flow space for the passage of air from the nozzle recess into which said sleeve fits into the contracting space between the ends of said plug and sleeve, and means for supplying air under pressure to the sleeve-recess of said nozzle.

3. A liquid fuel burner comprising a nozzle having a fuel supply duct within it, a plug fitting closely into a corresponding recess of said nozzle and having a duct forming a continuation of the duct of that nozzle, and contracting to a small discharge orifice, the discharge end of said plug tapering, and a sleeve surrounding said plug and fitting closely at one end into a corresponding recess of said nozzle, the other end of said sleeve having a discharge opening registering with the discharge opening of said plug, said sleeve formed internally to provide a contracting space between said sleeve and the discharge end of said plug, said plug being cut away at one or more points to provide flow space for the passage of air from the nozzle recess into which said sleeve fits into the contracting space between the ends of said plug and sleeve, said nozzle

having also a longitudinal eccentric air supply duct communicating with the sleeve-recess of said nozzle.

4. A liquid fuel burner comprising a nozzle having a fuel supply duct within it and having recesses of different diameters for reception of different members of an atomizing device, and an atomizing device connected to said nozzle and comprising inner and outer members having discharge orifices in line and having a contracting space between their ends, the inner of said members fitting into one of said orifices of the nozzle, the outer of said members screw connected to the inner of said members and having, in rear of its screw threaded portion, a relatively thin portion spaced away from the said inner member and fitting tightly in one of said recesses of the nozzle, means being provided for the supply of air under pressure to the space between said inner member and the relatively thin portion of the outer member, and thence to the contracting space between the ends of said inner and outer members.

In testimony whereof I have signed this specification in the presence of two subscribing witnesses.

LEON WYGODSKY.
